INVENTOR:
Joseph Rosenheim,
BY Geo. W. Meier
ATTORNEY

UNITED STATES PATENT OFFICE.

JOSEPH ROSENHEIM, OF CONEY ISLAND, NEW YORK.

RACE-GAME APPARATUS.

Application filed October 15, 1923. Serial No. 668,477.

To all whom it may concern:

Be it known that I, JOSEPH ROSENHEIM, a citizen of the United States, and resident of Coney Island, county of Kings, city and State of New York, have invented certain new and useful Improvements in Race-Game Apparatus, of which the following is a specification sufficient to enable those skilled in the art to which the invention appertains to utilize the same.

The object of my invention is to afford a simple but interesting aquatic race game requiring a moderate degree of skill and dexterity of manipulation on the part of the players, but sufficiently difficult to insure zest in competition; and the invention consists in the specific combination and arrangement of devices and appurtenances described and claimed, comprising essentially a plurality of individual race-way water tanks in each of which is placed a freely floatable vessel, each tank being formed at one extremity with a start-location and at the other with a signal device, and means under control of the player for causing air to impinge against said vessel to drive it into contact with said signaling device, all as hereinafter fully set forth.

In the accompanying drawings I exemplify, more or less symbolically and diagrammatically, means essential to the practical embodiment of the distinctive features of my invention, without limiting myself to the identical form and construction of parts and appurtenances shown, since modifications in minor detail, and mechanical expedients, may be resorted to with like results, and without departing from the spirit and intent of my invention in this respect.

With this understanding;

Fig. 1, represents a plan of adjacent individual race-way tanks, a dirigible float and means for manipulation thereof being shown in connection with one tank only, and omitted from the other for clearness of illustration;

Fig. 2, is what may be designated as a sectional elevation taken upon general plane of line 2—2 Fig. 1;

Fig. 3, is a sectional elevation illustrating one form of universal adjustment mount for an air projector;

Fig. 4, is an elevation showing an otherwise free air projector attached to a flexible tube;

Fig. 5, is a detail view of a magnetic con-

trol of the dirigible float when in start-location;

Fig. 6, a diagrammatic representation of a duplex electric circuit system adapted for use in connection with my plural race-way tanks.

Each tank T, is of sufficient length to afford a suitable race-way for a dirigible float F, which latter is preferably in the form of a boat or vessel, the length of which is greater than the width of the tank, so that said float F, can not be turned around or reversed in its tank.

Any suitable number of these race-way tanks T, T, are positioned side by side, two at least being necessary in order to provide for competitive play.

Each tank is formed with a start-location or "dock" D, D, in which its dirigible float F, is normally positioned centrally, as shown on the left hand side of Fig. 1, of the drawings; and is thus normally but releasably held in position in location by an armature a, on the rear or stern of the boat float F, in conjunction with a fixed permanent magnet m, located at the inner end of the dock D,—said magnet m, being of sufficient strength for the purpose, but of insufficient power to resist the force of air under pressure directed against the said float F.

This air pressure is directed and controlled by means of a nozzle N, suitably connected with a source of supply through the medium of a flexible conduit e, attached to a pipe p, leading to a pressure tank or equivalent means.

The nozzle N, may be mounted on a universal joint u, as indicated in Figs. 1, 2, and 3 of the drawings; or may be simply held in the hand of the player, if unmounted as in Fig. 4. In either case the nozzle N, is to be manipulated by the player in such manner as to cause air under pressure to impinge against the dirigible float F, for the purpose of driving the latter to the other extremity of the tank T, and into contact with the circuit closure plate K, by means of which an electric circuit E may be energized,—a suitable signal device or devices being interposed in said circuit E, as for instance a lamp l, or a bell b, or both, as may be found most desirable or expedient.

In the duplex electric circuit system shown in Fig. 6 of the drawings, pressure on the circuit closure plate K, energizes a solenoid

S, thereby causing the latter to close the signal circuit, this arrangement being duplicated for each tank, so that each is independent of the other; and the solenoids S, 5 being retracted upon occasion by means of a push button R, interposed in a circuit common to all. But it is to be understood that I do not limit myself to this or any other electric circuit system, the essential feature in 10 this respect being the closure of a signal circuit by means of the abutment plate K, when the float F, contacts therewith.

The dirigible float F, may be provided with a transverse sail-plate f, or equivalent 15 device for increasing air pressure surface. The degree of air pressure being the same for each nozzle N, the skill and patience of the players in competition is exercised in directing and maneuvering their respective 20 dirigible floats F, in order to be the first to contact with a signal plate K, thereby indicating the winner, and terminating the race.

Retractile means are provided for returning each float F, to normal position at the 25 start-location or dock D, as for instance a tow line t, attached to the rear of the float and winding upon a windlass w. In order to isolate the tanks T, and floats F, from extraneous interference, they are enclosed by 30 suitable means (indicated by i, in Figs. 1 and 2 of the drawings) that will insure this result while admitting of observation of the interior in each case.

What I claim as my invention and desire 35 to secure by Letters Patent is:

1. Race game apparatus of the character designated, comprising a plurality of individual race-way water tanks, each tank containing a dirigible float, each tank being 40 formed with a fixed start-location at one end and a signal device at the other, and with means adapted to be controlled by a player for directing air under pressure against said dirigible float, substantially in the manner and for the purpose set forth.

2. Race game apparatus of the character designated, comprising a plurality of individual race-way water tanks, each tank containing a dirigible float, each tank being 50 formed with a fixed start-location at one end and with an electric signal device at the other, and with means adapted to be controlled by a player for directing air under pressure against said dirigible float, substantially in the manner and for the purpose set forth.

3. Race game apparatus of the character designated, comprising a plurality of individual race-way water tanks, each tank containing an elongate dirigible float of greater 60 length than the width of the tank, each tank being formed with a fixed start-location at one end and a signal device at the other, and with means adapted to be controlled by a player for directing air under

pressure against said dirigible float, substantially in the manner and for the purpose set forth.

4. Race game apparatus of the character designated, comprising a plurality of individual race-way water tanks, each tank containing an elongate dirigible float of greater length than the width of the tank, and being provided with a transverse sail-plane, each tank being formed with a fixed start- 70 location at one end and a signal device at the other, and means adapted to be controlled by a player for directing air under pressure against said dirigible float, substantially in the manner and for the purpose set forth. 75

5. Race game apparatus of the character designated, comprising a plurality of individual race-way water tanks, each tank containing a dirigible float provided with a magnet-armature, each tank being formed at one end with a fixed start-location provided with a magnet for magnetic engagement with said armature on the float, the other end of the tank being provided with a signal device actuated by contact with said float, and means adapted to be controlled by a player for directing air under pressure against said dirigible float, substantially in the manner and for the purpose set forth. 85

6. Race game apparatus of the character designated, comprising a plurality of individual race-way water tanks, each tank containing a dirigible float, each tank being formed with a fixed start-location at one end and a signal device at the other, means adapted to be controlled by a player for directing air under pressure against said dirigible float, and means under the control of the player for retracting said float to the said start-location, substantially in the manner and for the purpose set forth. 90

7. Race game apparatus of the character designated, comprising a plurality of individual race-way water tanks, each tank containing a dirigible float, each tank being formed with a fixed start-location at one end and a signal device at the other, means adapted to be controlled by a player for directing air under pressure against said dirigible float, and means under the control of the player for retracting said float to said start-location, consisting of a tow line attached to said float and to a windlass, substantially in the manner and for the purpose set forth. 105

8. Race game apparatus of the character designated, comprising a plurality of enclosed individual race-way water tanks, each independently enclosed tank containing a dirigible float, each tank being formed with a start-location at one end and a signal device at the other, and with means adapted to be controlled by a player for 110

directing air under pressure against said dirigible float, substantially in the manner and for the purpose set forth.

9. Race game apparatus of the character
5 designated, comprising a plurality of individual race-way water tanks, each tank containing a dirigible float, each tank being formed at one extremity with a fixed start-
location and at the other extremity with a
10 signal device, and an air nozzle adjustably
mounted adjacent to said start-location, and
adapted to be controlled by a player for the
purpose of directing air under pressure
against said dirigible float, substantially in
the manner and for the purpose set forth.
